LOCK STRUCTURE

Emilio Straessli, Sao Paulo, Brazil

Application July 30, 1943, Serial No. 496,782
In Brazil August 27, 1942

2 Claims. (Cl. 292—38)

1

This invention refers to a lock structure for the bolting and unbolting of safes, strong-rooms and similar installations, and it has for its object to provide improved means for controlling the operation of such installations.

The apparatus comprises a system of flexible cables, embedded in the walls of the safe or similar installation and actuated by a control device whereby the locking bolts may be rendered operative or inoperative as desired.

In the annexed drawing:

Fig. 1 is a plan view of the device, operated directly.

Fig. 2 is a longitudinal sectional view of the same.

Fig. 3 is a plan view of another form of the device, operated from a distant point.

Figs. 4 and 5 schematically show the two forms of the device applied to use.

The device, Figs. 1 and 2, comprises a hand wheel 1, the shaft of which is secured to a gear wheel 2 meshing with a toothed plate 3 movable within two guides 4. The toothed plate 3 is fixed to a cross head 5, at right angle thereto and supporting one or several flexible cables 6. It is clear that the movement of the hand wheel 1 produces the sliding of the plate 3 and cables 6 and this motion is utilized for actuating the locks or bolts of the safe.

The cables 6 are guided by their sliding-guides 7. The sliding guides are fixed to a rigid support 8 and thus the cables 6 can be moved in order to actuate the locks.

The device may be operated from a distant point, as shown in Fig. 3 and for that purpose the gear wheel 2 is moved by a drum 9 embedded in the safe, and operated from a distant point by means of another cable 10 fixed to a steel band 11 wound upon the drum 9.

2

Figure 4 shows the device mounted in the rear or in a side wall of the safe, and operated from a distant point, through cable 10. The cables 6 are provided at their ends with suitable locks 12 which lock and open the safe, under control of the movement of the cables 6.

Figure 5 shows a similar installation, in which the locks are moved directly by the hand wheel 1.

What I claim is:

- 10 1. In combination, a plurality of locking members, a rotatable control member, a drum carried by the rotatable member, a steel band on said drum, a flexible operating member secured to said band, a bar movable longitudinally by said control member, a cross head carried by said bar, and a plurality of flexible actuating members secured to said head and to said locking members for actuating the latter in response to rotation of said control member.
- 15 2. An arrangement as claimed in claim 1 characterized by the provision of spaced guides for said bar and said flexible members arranged to limit movement of said cross head.

EMILIO STRAESSLI.
